CLAIM

The ornamental design for an insulating device, as shown and described.

DESCRIPTION

FIG. 1 is a top, front, left perspective view of an insulating device showing our new design in an open configuration;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, front, left perspective view of an insulating device showing our new design in a closed configuration;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken lines in the figures illustrate portions of the insulating device that form no part of the claimed design.

1 Claim, 14 Drawing Sheets

Related U.S. Application Data

a continuation of application No. 29/655,306, filed on Jul. 2, 2018, now Pat. No. Des. 910,382, which is a continuation of application No. 29/604,256, filed on May 16, 2017, now Pat. No. Des. 821,824.
